United States Patent Office.

D. J. CLARK, W. F. DOGGETT, AND S. M. BURR, OF COLUMBUS, OHIO.

Letters Patent No. 97,603, dated December 7, 1869.

IMPROVEMENT IN WOODEN TRUNKS.

The Schedule referred to in these Letters Patent and making part of the same.

To all whom it may concern:

Be it known that we, D. J. CLARK, W. F. DOGGETT, and S. M. BURR, of Columbus, in the county of Franklin, and in the State of Ohio, have invented certain new and useful Improvements in Wooden Trunks; and do hereby declare that the following is a full, clear, and exact description thereof, reference being had to the accompanying drawings, and to the letters of reference marked thereon, making a part of this specification.

The nature of our invention consists in the construction of trunks of bent wood, in such a manner that the sides and top are of one piece, and the ends and bottom of another.

In order to enable others skilled in the art to which our invention appertains, to make and use the same, we will now proceed to describe its construction and operation, referring to the annexed drawings, in which—

Figure 1 is a perspective view, and

Figure 2, a side elevation.

A piece of wood, A, of any desired size, is exposed to the action of steam, or by any other suitable means, so that it can be bent, as shown in the drawing, forming the sides—that is, the front and back—and the top of a trunk. Another piece of wood, B, is then bent in a similar manner, so as to form the ends and bottom, and the two pieces then fastened together, in proper position, by any suitable means.

The trunk thus formed is sawed in two, so as to

form the body and the lid, and one, two, or more wooden bands, C, are put around the trunk, said bands extending all the way around the same, giving a breakage of same in the one nearest to the lock, if found necessary to do so, as shown in fig. 1.

One band, C, should be placed at the edge of the lid, and another at the edge of the body of the trunk; or we may put a broad band right over the line where the trunk is to be sawed, and divide said band with the saw at the same time as the trunk is divided; or a band may be attached to the lid, and extend below the joint, so as to completely cover the same when the trunk is closed, in which case said band will have to be narrowed or cut off at the back, as seen in fig. 2, to allow the trunk to be opened.

Having thus fully described our invention,

What we claim as new, and desire to secure by Letters Patent, is—

A trunk formed of two pieces of bent wood, one piece forming the top and sides, and the other the bottom and ends, substantially as herein set forth.

In testimony that we claim the foregoing, we have hereunto set our hands and seals, this 8th day of September, 1869.

D. J. CLARK. [L. S.]
W. F. DOGGETT. [L. S.]
